United States Patent Office

Des. 190,131
Patented Apr. 18, 1961

190,131

TRAY

Aaron Traum, New York, N.Y., assignor to David Traum, Incorporated, New York, N.Y., a corporation of New York

Filed June 1, 1960, Ser. No. 60,811

Term of patent 14 years

(Cl. D44—10)

FIG.4

Fig. 1 is a perspective view of a tray showing my new design;

Fig. 2 is a bottom plan view thereof;

Fig. 3 is a side elevation thereof; and

Fig. 4 is an end elevation thereof.

I claim:

The ornamental design for a tray, substantially as shown.
